United States Patent Office.

OLE BULL, OF NEW YORK, N. Y.

Design No. 4,468, dated November 15, 1870.

DESIGN FOR A PIANO.

The Schedule referred to in these Letters Patent and making part of the same.

To all whom it may concern:

Be it known that I, OLE BULL, professional musician, of Valestrand, near Bergen, Norway, residing much of the time in the city, county, and State of New York, have invented a certain new and ornamental Design for the Exterior of Pianos.

I have constructed a piano according to my improved design.

Accompanying this are photographs therefrom, which form a part of this specification.

That marked Figure 1 is a front view.

That marked Figure 2 is a view from the right.

That marked Figure 3 is a view from the left.

That marked Figure 4 is a diagonal perspective view, showing the piano with the top raised.

Similar letters of reference indicate like parts in all the figures.

There has lately come in vogue a rich ornamentation, understood to be a revival of an ancient style, and generally known by the name of a lady of the Parisian court—Madame Pompadour—as the Pompadour style.

It has been before applied to chairs, sofas, bureaus, and bedsteads.

My design is an application of this ancient Pompadour style of ornamentation, or rather a modification partaking also of what is known as style *Renaissance* and *Neo Grec*, to the modern instrument known as the piano-forte.

Referring to the letters of reference on the photographs—

A is the body;

B, the main top;

C, the ogee front;

D, the lyre or assemblage of pedals, and their connections; and

E E E, the legs.

G is the desk on which the music-sheets are placed.

My piano is constructed of the best materials, and has points of importance in its principles of construction and mode of operation; but my design will allow equally well for the ordinary approved modes of construction and operation.

The ornamentation according to my design is of the most elegant and chaste character.

Figures are traced by the lines *m m* sunk and gilded, representing olive-branches, panels, scrolls, and analogous devices, tastefully disposed as represented.

There may be also carved heads, branches, scrolls, &c., as indicated by *p p*.

I claim as my invention—

The design for a piano, as described and shown.

In testimony whereof I have hereunto set my name in presence of two subscribing witnesses.

Witnesses:

OLE BULL.

THOMAS D. STETSON,
C. C. LIVINGS.
